ADJUSTABLE FEED SHELVES FOR PAPER
HANDLING MACHINERYVerneur E. Pratt and George F. Gray,
Norwalk, Conn.

Application October 6, 1945, Serial No. 620,708

6 Claims. (Cl. 271—86)

1

This invention relates to adjustable feed shelves for paper handling machinery, and has for an object the provision of an adjustable feed shelf for flow cameras such as disclosed in the copending application Serial Number 507,939, filed October 28, 1943, entitled: "Photographic devices and method of operating same," but may be used in any device where it is desirable to feed papers of different widths to conveyor belts or the like to be photographed, printed, stamped, or processed in any manner in the machine to which the feed shelf is attached.

Another object is to provide a feed shelf of the character described which is free from all transverse joints or cracks in which the ends of papers may catch during the feeding operation.

A further object is to provide a feed shelf that is easily adjustable to take papers of any width.

Other objects and advantages will appear from a perusal of the following specification and accompanying drawings, where by way of illustration the invention is shown as applied to a flow camera as disclosed in the aforesaid copending application. It will be understood, however, that the showing herein is not limitative, the invention being as defined in the appended claims.

In the accompanying drawings:

Figure 1 is a plan view looking down on the feed shelf constituting this invention;

Figure 2 is a transverse cross-sectional view on the line 2, 2 Figure 1;

Figure 3 is a transverse view partly in section on the line 3, 3 Figure 2;

Figure 4 is a side view of the feed shelf shown in the preceding figures attached to a flow camera as described in the aforesaid copending application; and

Figure 5 is a detail view of the snap fasteners on the inner ends of the shelf whereby same is secured to the device or machine with which it is used.

Referring to Figure 1, the numeral 10 denotes a support having forwardly extending ears 11, 12 adapted to fit into slotted plates 13, one on each side of the device to which the feed shelf is attached and secured thereto by welding or in any suitable manner.

Each of said ears has a snap fastener comprised of a flat spring 14 secured to the ear at 15 and having at its free end a plunger 16 adapted to enter a hole in the side walls 17 of the device such as the flow camera generally indicated by the numeral 18.

The support 10 carries upon its upper face the transverse sliding members 19, 20, 21, 22.

2

The slides 19, 20 have secured thereto in any suitable manner the chute member 23 and the slides 21, 22 have the chute member 24 likewise secured thereto.

5 The bottom portions of the chute members are corrugated as shown at 25 and nest one within the other as best seen in Figure 2. This forms a horizontal feeding table, the corrugations running in the direction in which material is fed 10 thereover to the device 18.

The sliding members or arms 19, 20, 21, 22 are slotted as shown at 26, Figure 3, where they extend below the chute members. (Two of these arms, 19 and 21 are shown so slotted in Figure 15 3.) Bolts 27, 28 extend through these slots and the support 10. Wing nuts 29, 30 are provided for the threaded outer ends of the bolts 27 to secure the parts together as hereinafter described.

The chute is assembled by placing the parts together as shown in Figure 2. The ears 11, 12 are then pushed into the slots in plates 13 and the plungers 16 of the snap fasteners on these ears enter the holes in the side walls 17 of the device. Thus the chute is mounted thereon.

25 The chute members are now adjusted to take papers of any width up to the capacity of the device, as they may be moved from the extreme outer position shown in dotted lines 23a, 24a, Figure 1 to the inner position shown in solid 30 lines. This is accomplished by raising the member 23 so that the corrugations in the bottom thereof no longer mesh with the corrugations in member 24, and then 23 and 24 are shifted bodily to the desired position and clamped by bolts 27, 28 35 and nuts 29, 30.

The outer ends or horizontal ears 31, 32 of the chute members extend into the device 18 as best seen in Figure 4 to guide the papers fed into the chute to the mechanism of device 18 which, 40 in the case of the flow camera described in the aforesaid copending application, is the belts 33, 34.

To detach the device it is only necessary to pull outwardly on the knobs 35 to release plungers 16 and thereby release the chute from the device 18.

45 It will be observed from the foregoing description and the drawings that this improved chute has no transverse cracks or slides for papers to catch. The corrugated bottom facilitates the feeding of papers as the papers rest on the tops 36 of the ridges therein. This is an advantage over chutes having a smooth bottom against which the papers often lie and stick because of 50 static electricity and for other reasons. The

only seam in the bottom of the chute is at 37 and this runs in the direction of the paper feed and is therefore not objectionable, particularly as it lies below the tops of the ridges 37 and therefore the paper does not touch it.

The chute can be easily adjusted to feed papers at any point across the throat or intake of the device 18. The chute member 23 can be positioned to feed papers on the extreme left of the feeder belts 33, 34 and the chute member 24 can be moved to vary the width of the chute. However, by making both chute members adjustable, papers may be fed to the feeder belts at any point transverse the belts.

By "corrugations" is meant any conformation of the bottoms of the chute members that permits nesting one within the other whereby the inventive concept herein disclosed may be attained, which is to provide an adjustable chute having no transverse cracks, points or ridges that may interfere with the smooth feeding of paper lengthwise therealong. It will be observed that the feed shelf can be attached and removed from the machine or device 18 without in any way disturbing the adjustment of the width of the feed chute formed by the members 23, 24.

What is claimed is:

1. In a device of the character described, a support, corrugated members nested one within the other to form a feed shelf having opposed longitudinal sides formed by the upturned edges of said members, and means comprising clamping members secured to said corrugated members and underlying said corrugated members and extending transversely thereof for securing said corrugated members to said support, said corrugations running lengthwise of the upper surfaces of said members whereby flat sheets fed thereover rest upon the apexes of said corrugations and are held out of contact with the depressed spaces therebetween, whereby sticking of the sheets to the support is prevented.

2. In a device of the character described, corrugated members adapted to nest one within the other to form a feeding shelf having opposed longitudinal sides formed by the upturned edges of said members, said corrugations running in the direction in which material is fed thereover whereby flat sheets fed by said support rest upon the apexes of said corrugations and are held out of contact with the depressed spaces therebetween whereby sticking of the sheets to the support is prevented, arms extending below said members and secured thereto and underlying the bottom surfaces thereof extending transverse said members, and means for securing said arms

together whereby said members may be laterally spaced apart in various adjusted positions with some of said corrugations nested and so held together by said means.

5. In a device of the character described, a support, clamping means carried thereby and corrugated members forming a feeding table overlying said support and adapted to be clamped thereto by said means in various positions thereon whereby the width of said feeding table may be altered, said corrugations being nested the while, said corrugations running in the direction in which material is fed over said table and being adapted to support flat sheets upon the apexes of said corrugations while said sheets are fed therealong.

4. The device as claimed in claim 3, wherein said support has means independent of said corrugated members for attaching same to a machine with which said device is to be used to position said corrugated members with the corrugations extending towards the machine.

5. The device as claimed in claim 3, wherein said support has means for attaching same to a machine including ears extending from the main body thereof, and said corrugated members have extending ears adapted to guide material fed along said corrugated members and into a machine adjacent said ears.

30. 6. In a device of the character described, a chute comprising two sections of corrugated material adapted to overlap and nest in the corrugations whereby the width of said chute may be adjusted, means for adjusting the width of said 35 chute comprising a pair of members one of each being secured to one of said sections and underlying same, one of said members extending below the other to cause some of the corrugations of each section of said chute to mutually engage, whereby the width of said chute may be varied.

VERNEUR E. PRATT,
GEORGE F. GRAY.
